ADJUSTABLE CAM MECHANISM

George F. Daly, Endicott, N. Y., assignor to International Business Machines Corporation, New York, N. Y., a corporation of New York

Application December 6, 1944, Serial No. 566,804

1 Claim. (Cl. 74—568)

1

The present invention relates to an altimeter drum and drive mechanism therefor designed for use in connection with training apparatus of the type shown and described in a publication of August, 1944, entitled "Operation, Service and Overhaul Manual, Device 7-A-3, Horizontal Bombing and Dead Reckoning Trainer, Volume I of two volumes, published under the joint authority of the Commanding General, Army Air Forces, the Chief of the Bureau of Aeronautics and the Air Council of the United Kingdom." A copy of this publication exists in the files of the United States Patent Office.

Briefly, by means of such a training apparatus, a student bombardier is confronted with conditions that closely simulate those which occur during actual flying and which are intended to produce proficiency in the art of bombing. The particular apparatus with which the present invention is associated is in the form of a bombing and dead reckoning trainer which has been designed to duplicate to the utmost degree the flight of an airplane on an actual bombing mission, while at the same time enabling the instructor to observe the bombardier's reactions and give him valuable advice as to his procedure. The apparatus includes, among other things, a bombardier's station wherein the bombardier, in position with his instruments, may view an image of a realistic target which appears to move toward him at a uniform velocity. This target is in the form of a motion picture projected from an overhead projection apparatus onto a screen below the bombardier so that during a bombing run in the trainer the bombardier may take the necessary sights, make the necessary calculations of altitude and airspeed, manipulate his instruments, etc., and otherwise perform all the necessary duties that would be required of him during an actual bombing run.

The invention is primarily concerned with an instructor's control station and equipment therefor wherein the instructor is provided with the necessary instruments for setting up bombing problems, together with means for checking the actions of the bombardier.

Still more specifically, the present invention relates to an altimeter drum assembly and drive unit therefor which are enclosed together with other equipment in the instructor's instrument panel casing. By means of this equipment, true altitude and average temperature readings which the student bombardier is required to make is made available to the instructor automatically. Briefly, the altimeter drum and drive mechanism

2

therefor comprises a panel proper behind which a drum unit including an altimeter drum per se, is mounted for rotation about a horizontal axis. Surrounding the drum and concentric therewith is a drum shutter mounted for independent turning movement about the common axis of the drum. Printed or otherwise marked on the surface of the drum are certain visible indicia representing indicated altitude and certain other indicia representing true altitude. The readings afforded by these indicia are visible through an elongated horizontally extending window or slot provided in the outer instructor's instrument panel. The various indicia are arranged in circumferential bands or columns around the surface of the drum, one column pertaining to indicated altitude readings and the remaining columns pertaining to true altitude readings.

The drum shutter is provided with an elongated opening through which the indicated altitude readings are visible, while a straight reference line is provided for selecting these readings. The true altimeter readings are selectively visible through the various windows, the latter being arranged at spaced offset points along the shutter.

Available temperature readings are provided by means of indicating marks on a scale extending alongside the drum and shutter and these latter readings are adapted to be selected by virtue of the positional relationship of the various openings in the shutter which come into alignment with the slot in the instructor's panel as the drum and drum shutter are moved relative to each other.

From the above description it will be seen that indicated altitude readings are a direct function of the position of the drum at any particular instant, while true altitude readings are a combined function of the position of the drum and of the shutter relative to the latter. Average temperature readings are a function of the position of the shutter relative to the slot or window provided in the instrument panel. The altitude drum is adapted to be driven in either direction at a predetermined rate of speed by means of an electric motor. Rotation of the drum in one direction is representative of the climb operation, while rotation thereof in the opposite direction is representative of a dive operation. Reset means are provided for restoring the drum to its initial or zero indication.

The position of the drum shutter is adapted to be varied by means of a cam cluster slidably mounted or keyed to a cam shaft. The cam shaft is coupled in direct driving relationship to the

55

shaft upon which the drum is mounted. The cam cluster is adapted to be shifted to bring a selected cam thereof into register with the cam follower and the latter is mechanically connected to the drum shutter in such a manner that as the drum and cams rotate the cam follower causes the position of the shutter to be varied.

Each cam in the cluster represents a particular problem requiring different calculations on the part of the student bombardier due to temperature variations. The result of these calculations are made immediately available to the instructor and this is made possible by the expedient of altering the position of the drum shutter under the control of the particular cam which has been selected for operation. The true altitude reading is thus made available to the instructor and at any particular instant true altitude will be represented by the particular position of the drum and a particular position of the shutter. The average temperature readings are available to the instructor on the average temperature scale and is a function solely of the position of the shutter.

Other objects of the invention will be pointed out in the following description and claim and illustrated in the accompanying drawings, which disclose, by way of example, the principle of the invention and the best mode, which has been contemplated, of applying that principle.

In the drawings:

Fig. 1 is a perspective view of an instructor's station including the instructor's instrument panel comprising the present invention.

Fig. 2 is an enlarged perspective view of the instructor's instrument panel assembly with the panel cover removed to more clearly illustrate the nature of the invention.

Fig. 3 is a side elevational view of an altimeter drum employed in connection with the present invention.

Fig. 4 is an end view of the altimeter drum.

Fig. 5 is a fragmentary perspective view of an altimeter drive unit employed in connection with the present invention.

Fig. 6 is another perspective view of the altimeter drive unit taken from a different angle.

Fig. 7 is still another perspective view of the altimeter drive unit, certain parts being broken away to more clearly reveal the nature of the invention.

Fig. 8 is an end view of the altimeter drive unit.

Referring now to Fig. 1, the instructor's instrument panel is located at a central position on the instructor's desk 36 and consists of three major assemblies, namely, an operating instrument panel 70, an altimeter drum unit 72 and an altimeter drive unit 74 (see particularly Fig. 2). The instrument panel has associated therewith a conventional clock or time piece 76 which has no internal mechanism or electrical connections and which is secured to an instrument panel cover 38.

A true airspeed indicator 80, which is designed to indicate the true airspeed as it exists at the projector of the trainer under the control of the instructor, is mounted on the panel cover 38 at the right of the clock 76.

An indicated airspeed instrument 82, also mounted on the cover 38, is provided in order that the instructor may instantaneously determine the airspeed that would be read on the bombardier's airspeed indicator in the trainer at the

altitude and temperature of the particular problem under consideration. A compass 84, which is mounted on the panel cover at the right of the instructor's true airspeed indicator 80, indicates to the instructor the airplane heading.

A drift meter 98 on the panel cover 38 indicates to the instructor the angular relation of the image to the bombardier's compartment in the trainer. A temperature meter 100 of conventional design, and which may be a central reading voltmeter, is also mounted on the panel cover 38 and is provided for the purpose of giving the instructor the temperature reading at any altitude in accordance with certain cam selections of which he is capable of making and the nature of which will be described presently.

Referring now to Figs. 1, 3 and 4, at the left-hand side of the panel cover 38 is an opening or window 104 through which there is visible an altimeter drum per se 106 (Fig. 2) which is associated with the drum unit assembly 72. The drum 106 is mounted on a horizontal shaft 108 (Fig. 3) which is supported in bearings 110 and 112 carried in a pair of side plates 114 and 116 that project upwardly from and are secured as at 118 to a pair of cross members 120. The drum proper consists of a cylindrical sheet of parchment or other similar material (Fig. 4) which is mounted on a plurality of spiders 124 which are keyed or otherwise secured to the shaft 108. The inner or right-hand end of the shaft 108 projects completely through the side plate 116 and has mounted thereon one element 126 (Fig. 3) of a drum coupling, the other or counterpart element of which is shown at 128 in Fig. 6 and is associated with the altimeter drive unit 74. The two coupling members 126, 128 are provided with a centering pin and hole arrangement 127.

A pair of arms 130 which are secured as at 132 to the side plates 114 and 116 project upwardly at the sides of the drum 106 and serve to support therebetween a pair of tightly stretched parallel indicating wires 133 which serve as a reference line for reading two sets of figures or indicia IA and TA respectively, the former meaning indicated altitude and the latter meaning true altitude. The indicia IA are arranged in an extreme left-hand band or zone extending around the surface of the cylindrical drum, while the indicia TA are arranged in a plurality of similar columns existing in the medial longitudinal regions and also at the extreme right-hand end of the drum.

A drum shutter 134 (Figs. 3 and 4) of substantially semi-cylindrical design, and which is positioned in close proximity to the drum proper 106, is swingably supported between a pair of spiders 136, which are mounted on sleeves 140 for free turning movement on the shaft 108. The shutter 134 is provided with an elongated opening 142 adjacent its left-hand end, as viewed in Fig. 3, through which the indicia IA representing indicated altitude are visible when these latter indicia are aligned with the window 104 formed in the panel cover 38. The shutter 134 is also provided with a series of diagonally or helically arranged windows 144 of a number equal to the number of true altitude columns on the drum and each of which is aligned for movement in register with a respective true altitude column. At this point it may be stated that the altitude drum is adapted to be driven at a predetermined rate of speed by means of a motor M (Fig. 2) associated with the altimeter drive unit 74 operating through the internal drive mechanism of the unit in a manner that will appear presently. The drum may be

driven for a gradual climb or a gradual dive under the control of a pair of switches C and D respectively and mounted on the front of the instructor's panel assembly. A rheostat control knob 146, likewise mounted on the front of the panel assembly, serves to control the rate of climb or dive, as the case may be, by permitting the rate of speed at which the drum is turned to be varied at the will of the instructor. The various indicia or figures IA and TA progress arithmetically as they appear through the window 104 when the drum is rotated in a clockwise direction, and consequently when the drum is thus rotated a climb is in progress. Conversely, when the drum is rotated in the opposite direction a dive is in progress. An altimeter reset switch unit AR is provided in the grouping of control devices just described and exists for the purpose of restoring the drum to its zero indication at a comparatively rapid rate of speed. A climb indicator 147 and a dive indicator 149, which are in the form of panel lights, are provided immediately below the climb and dive switches C and D.

True altitude readings and average temperature readings which the bombardier is required to calculate are made available to the instructor automatically. The altitude readings are made available by virtue of the drum position and these readings are taken respectively through the openings 142 and 144 in the drum shutter. Average temperature readings are taken directly from a scale 105 positioned below the opening 104 and having indicia thereon which are identified by their alignment with the particular opening 144 appearing in the window 104. The particular problem at hand, selected by the instructor, is automatically entered into the drum reading by means of a plurality of average temperature correction cams and altitude correction cams disposed in two groups. As will be explained later, since the altitude correction factor involved is in part dependent upon the free air temperature, the latter altitude correction cams are herein-after referred to as free air cams. The average temperature cam group is designated in its entirety at 148, while the altitude or free air cam group is designated at 214. While any desired number of cams within the limits of mechanical expediency may be employed, for purposes of illustration in the present instance six such cams have been shown in the first group and are designated reading from left to right in Fig. 5 as a, b, c, d, e, f, and a similar number of cams appear in the second group and are designated reading from left to right at a', b', c', d', e', f'. Each of these cams represents a particular problem requiring different calculations on the part of the bombardier due to altitude or temperature variations. Insofar as temperature is concerned, the cams in the group 148 are caused to alter the drum reading or set thereto a correction factor by the expedient of altering the position of the drum shutter 134 in steps which, because of the fact that there are six cams, may assume at the will of the instructor, any one of six initial starting positions. Toward this end these cams are each provided with circumferential cam surfaces which are provided with relatively abrupt degrees of eccentricity. The true altitude reading of the drum will, therefore, at any given instant be the combined product of the particular position of the rotating drum and of the particular position of the drum shutter 134. The cams 148 are also designed to eliminate the necessity of the instructor performing the same calculations that are

required of the bombardier in making temperature readings at each 1,000 foot level during a climb to determine the corrected altitude. By reading the scale 105 below the window 104 and aligned with one of the openings 144 in the shutter 134, the instructor may tell at a glance the average temperature that would be obtained by taking temperature readings at each one-thousand feet on the bombardier's free air indicator.

10 The means whereby the position of the shutter 134 may be shifted at will and whereby selection of the various cams a, b, c, d, e or f may be made is best illustrated in Figs. 2, 5 and 6. In this last figure only a single cam of the group 148, namely 15 the cam b, is shown. The remaining cams of the group have been omitted, while at the same time various parts of the altimeter drum drive assembly have been omitted or broken away to more clearly reveal the nature of the invention. The cam group 148 is mounted on or integrally formed with a sleeve 150 which is slidably keyed as at 151 to a shaft 152 hereinafter referred to as the cam shaft. The previously mentioned element 128 of the drum coupling 126, 128 is mounted on 20 the extreme left-hand end of the cam shaft 152 as viewed in Fig. 6. The coupling element 128 is formed with a pin 154 in its peripheral region and extends into a slot 156 (Fig. 4) formed in the coupling member 126, and thus the drum is adapted to be directly driven from the cam shaft 152. The cam shaft 152 is rotatably carried in a 25 pair of end plates 157 and 159 (Fig. 6) that extend upwardly from a plurality of base members or cross pieces 161 that form a support or base for the altimeter drive unit 74.

30 The various cams a, b, c, d, e and f are adapted to be shifted laterally along the shaft 152 so as to be selectively moved into register with a cam follower 158 carried at the free end of an arm 160. 35 The arm is secured to and movable with a shaft 162 which for descriptive purposes will herein-after be referred to as the average temperature shaft. This shaft is pivotally mounted in the end plates 157 and 159 and carries at one end 40 thereof a coupling member 164 similar to the coupling element 128 and which has for its counterpart a member 166 mounted on a shutter rock shaft 168 (Fig. 4), the ends of which are rotatably journaled in the side plates 114 and 116 45 of the altimeter drum unit 72. The shutter sleeves 140 have mounted thereon a pair of gears 170 (Fig. 3) at opposite ends of the drum and these gears have meshing therewith the toothed edges of a pair of segments 172 mounted on the 50 shaft 168.

55 Referring now to Figs. 5 and 6 wherein the means for shifting the cam group 148 to make selection of the various cams a, b, c, d, e or f is best illustrated, the cam sleeve 150 is formed with 60 a cylindrical groove 173 in a medial region which cooperates with a cam shift fork 174 which projects upwardly from a cam shift rack 176 having a series of gear teeth 178 formed in its underneath side. The teeth 178 are adapted to mesh 65 with an elongated gear 180 carried at the inner end of a rod 182 which is slidably carried in a U-shaped bracket 184 and which projects through the front wall of the panel unit. A spring 185 surrounds the rod 182 and normally biases the 70 same inwardly of the apparatus to an inoperative position. The outer end of the rod 182 carries a cam shift knob 186.

75 Still referring to Figs. 5 and 6, a cam shift interlock lever 188 is pivoted medially of its ends on a pivot stud 190. The lever 188 is provided

with an upstanding pin 192 that projects into a groove 194 formed in a collar 196 mounted on the rod 182. Thus it will be seen that shifting movement of the rod 182 by means of the cam shift knob will be accompanied by horizontal rocking movement of the lever 188. The interlock lever 188 is provided with a downwardly turned flange 198 through which there projects a cam shift interlock thrust rod 200 carrying at its outer end a cam shift interlock knob 202. The inner end of the thrust rod 200 is formed with a thrust pin 204 designed for engagement with the lower end of a lift arm 206 in the form of a bell crank lever mounted on the average temperature shaft 162 and the upper end of which lever carries a pin 208 which underlies the upper end of an average temperature lift arm 210 which is secured to the average temperature shaft 162. A conventional dash pot including a cylinder 187 secured within the bracket 184 and having a piston 189 operatively connected to the extreme right-hand end of the interlock lever 188, as shown in Fig. 5, serves as a cushioning device to prevent clashing of parts during manipulation of the cam release instrumentalities. From the above description of parts it will be seen that pushing in on the cam shift interlock knob 202 will operate to rock the average temperature shaft 162 about its axis and lift the cam follower 158 out of engagement with the particular cam *a*, *b*, *c*, *d*, *e* or *f* with which it is in register. When this is done the cam shift knob may be rotated so as to cause the gear 180 to operate on the gear teeth 178 and shift the cam shift rack 176 in one direction or the other and thus bring a selected cam *a*, *b*, *c*, *d*, *e* or *f* into register with the cam follower 158. At the same time, pushing in on the cam shift interlock knob 202 will operate through the drum shutter coupling 164, 166, to swing the drum shutter 134 about its axis toward a position of maximum reading. Referring now to Fig. 5, the bracket 184 has formed thereon a series of forwardly projecting pins 179 which are designed for selective registry with an equal number of holes 181 formed in a locating disc 183 mounted on the rod 182. The spacing of the pins 179 and of the holes 181 is such that when registry occurs therebetween a particular selected cam in the group 148 will fall into register with the follower 158 and similarly, a particular selected cam in the group 214 will fall into register with a follower 232. With the pins and holes in register, the cam sleeve 150 will thus be locked in a selected position of adjustment.

Still referring to Figs. 5 and 6, the previously mentioned series of six free air cams 214 are formed on the sleeve 150 and are provided for the dual purpose of controlling the reading of the free air temperature meter 100, as well as for the purpose of entering a temperature correction factor into the calculation for indicated airspeed as shown by the indicator 80.

The first of these functions is accomplished by means of a potentiometer 216 (see also Fig. 8) which is adjustably mounted in brackets 218 and 220 affixed to the end plate 157 and having associated therewith a sliding contact 224 carried at the lower end of an arm 226 that depends from a rock shaft 228 hereinafter referred to as the free air temperature shaft.

The shaft 228 is supported between the end plates 157 and 159 and carries an arm 230 that projects forwardly to the vicinity of the cam group 214 and is provided with the cam follower

232 designed for selective engagement with the various cams *a*', *b*', *c*', *d*', *e*' and *f*' of the group. At the rear of the unit there is mounted a fixed potentiometer 217 (Fig. 2) and a trimmer 219, fixed potentiometer 217 and variable potentiometer 216 are arranged in an electrical circuit which is in the form of a Wheatstone bridge circuit that operates to establish the position of the pointer associated with the free air temperature indicator 100 as set forth in the above mentioned divisional application. It is to be noted that pushing in on the cam shift interlock knob 202 will operate through the medium of the pin 208 to elevate an arm 234 which is affixed to the shaft 228. Such rocking movement of the arm 234 serves to rock the shaft 228 about its axis and cause the arm 230 to become elevated away from the particular cam with which it is associated so that shifting of the cam shift rack 176 may be resorted to.

In Fig. 6 a switch S is shown as being mounted immediately rearwardly of the cam shift interlock lever 188. This switch is adapted to be engaged by this latter lever when the interlock knob 202 is pushed inwardly to open the circuit to the driving motor M.

The second of the above mentioned functions of the six free air cams in the group 214 is accommodated through the medium of an airspeed correction unit designated in its entirety at 238 Fig. 2 and is driven during climb or dive operations and consequently during movement of the altimeter drum 106. The driving connection for direct driving of the airspeed correction unit 238 from the motor M during climb and dive operations, as well as the connections therefor whereby the free air temperature correction factor involved is entered into the airspeed indicator 82, will be set forth in detail after a description has been given of the driving connection existing between the motor and the altimeter drum 106. The driving connection just referred to includes a gear reduction unit 240 Fig. 7 whose input is a motor shaft 242 of the motor M and which at its output side serves through a pair of bevel gears 241 and 243 to drive a gear reduction train designated in its entirety at 244 leading to a driving gear 246 mounted on one end of the cam shaft 152 and which is directly coupled to the drum 106 by means of the coupling 126, 128. The gear 246 meshes with an altitude correction entry gear 250 which constitutes one input gear associated with the air-speed correction unit 238.

The airspeed correction unit 238 is in the form of a removable assembly complete in itself. This assembly forms no part of the present invention and is included as part of the subject matter of the above mentioned divisional application.

The airspeed correction unit 238 includes a casing 252 (Fig. 2) which is secured in position between the two end plates 157, 159. The mechanism includes a multiple differential gear system which receives its initial drive from a gear 256 shown between the drum unit 72 and the drive unit 74 in Fig. 2 and hereinafter referred to as the true airspeed entry gear. This latter gear is adapted to be manually driven by the instructor by means of an airspeed crank 258 (Fig. 1) located at the instructor's set-up panel 46 and serves to set a reading of true airspeed into the true airspeed indicator 80. The driving connection just referred to leads from the crank 258 through a pulley and cable system 262 to a drum 75 or pulley 264 at the extreme right-hand side of

the panel unit and which is shown at the left-hand side of Figs. 2 and 7.

The pulley 264 is mounted on one end of a shaft 265 (see Figs. 2, 5, 6 and 7) and which has mounted on its other end a gear 268 (Fig. 6) hereinafter referred to as the true airspeed drive gear. The gear 268 meshes with a gear 270 loosely mounted on the shaft 152 behind the coupling member 128 (Fig. 6) which in turn meshes with the true airspeed entry gear 256.

In actual practice, using standard instruments, the computing means for calculating true airspeed from indicated airspeed is based upon a logarithmic scale, the reading in knots obtained on the dial of the true airspeed indicator 80 as well as on the dial of the indicated airspeed instrument 82 are expressed by graduations that are spaced logarithmically. Thus, the airspeed correction unit 238 is provided with a logarithmic correction mechanism for changing the linear factor introduced by the entry gear 256 into a logarithmic factor and introducing the same into the true airspeed indicator 80. This mechanism forms the subject matter of the above mentioned divisional application and no detailed description or illustration thereof is made herein.

It is sufficient for the purpose of the present disclosure to state that the airspeed correction unit 238 receives an input from gears 250 and 256 in order to properly operate according to a logarithmic scale the true airspeed indicator 80 and the indicated airspeed instrument 82. In addition, and as previously stated, the reading of the instrument 82, in addition to being a function of the true airspeed, is also a function of the free air temperature and of the altitude at the instant of reading. Temperature correction is entered under the influence of the cam group 214 including the cams a' , b' , c' , d' , e' , and f' into the instrument 82 by means of a segment 334 mounted on the free air temperature shaft 228. This segment is adapted upon rocking movement of the shaft 228 under the influence of any one of the selected free air cams in the group 214, to impart movement to a gear 336 (Fig. 2) included in the multiple differential gear system of the airspeed correction unit 238. Thus this latter gear 336 constitutes a further input for the unit 238, the details of which have been set forth in the above mentioned divisional application.

While there have been shown and described and pointed out the fundamental novel features of the invention as applied to a preferred embodiment, it will be understood that various omissions and substitutions and changes in the form and details of the apparatus illustrated and in its

operation may be made by those skilled in the art, without departing from the spirit of the invention. It is the intention, therefore, to be limited only as indicated by the scope of the following claim.

What is claimed is:

In an apparatus of the character described, a rotary cam shaft, a sleeve slidably splined to said shaft, a cam cluster mounted on said sleeve and including a plurality of cam elements arranged in spaced relationship, a cam follower mounted for movement in a vertical plane and designed for selective engagement with said cams, means normally maintaining said follower in engagement with a selected cam, and selecting means for shifting said sleeve longitudinally of the shaft on which it is mounted comprising a cam shift rack mounted for sliding movement longitudinally of the shaft, there being a groove formed in said sleeve, a cam shift fork carried by said rack, there being a series of teeth formed on said rack, a gear cooperating with said rack and movable transversely of said shaft, an operating rod secured to said gear, locating means for said operating rod whereby the latter may assume a number of angular positions corresponding to the number of cams on said sleeve and whereby in any selected angular position of the rod a selected cam will be in register with said follower, said rod being movable from a retracted position wherein said locating means is inoperative to prevent turning of the rod to an advanced position wherein said rod is locked against turning movement, and means for elevating said follower out of the path of movement of said cams upon movement of said operating rod to its retracted position.

GEORGE F. DALY.
